BATHROOM HOLDER FOR A SPRAY CAN OR THE LIKE

Victor E. Lane, 2424 Kings Highway,
Brooklyn, N.Y. 11229

Filed Aug. 25, 1967, Ser. No. 8,392

Term of patent 14 years

(Cl. D33—21)

FIG. 3

FIG. 2

FIG. 1

FIG. 1 is a top plan view of a bathroom holder for a spray can or the like showing my new design;

FIG. 2 is a front elevational view thereof;

FIG. 3 is a side elevational view thereof;

FIG. 4 is a rear elevational view thereof;

FIG. 5 is an elevational view taken from the side opposite that shown in FIG. 3; and

FIG. 6 is a bottom plan view thereof.

The broken line representation of a spray can shown in the figures is for purposes of illustration only.

I claim:

The ornamental design for a bathroom holder for a spray can or the like, as shown and described.
